TYPEWRITING MACHINE

Fritz Ebert, Munich, Germany, assignor of one-half to Hermann Stark, Munich, Germany

Application July 2, 1931, Serial No. 548,368, and in Germany June 11, 1930

2 Claims. (Cl. 197—85)

Practically all of the many known typewriting machines, although partly highly developed leave nevertheless much to be desired. I mention especially in most cases the too heavy touch, the complicatedness of the step-by-step motion mechanism for the carriage, the many repairs and the expenses incurred for keeping the machines in proper working state. All these and other drawbacks are completely done away with 10 by the present invention by which the mechanism for moving the carriage in steps is considerably simplified, the manufacturing costs are considerably reduced and the lifetime of the machine is considerably lengthened, apart from 15 other advantages, as for instance very easy touch, doing away with repairs, etc. etc. A particular feature of the improved mechanism is this that springs are completely obviated so that the touch can be very light and the writer can, therefore, write by far longer than is possible with 20 the other machines in which the force of springs counteracting the touch must be overcome. In the other machines the springs cannot be dispensed with, as the strength of the blow of the 25 types upon the paper on the carriage depends greatly upon them. This is no more the case in my improved machine which, therefore, is also not subject to the disadvantages resulting from the existence of the springs. The greater simplicity of this improved machine permits of a 30 more robust use in unskilled hands, that is to say, it is by far less sensitive, as a lot of parts otherwise requisite in the construction are now lacking.

35 The chief improvement resides in the novel step-by-step motion provided for the carriage, the arrangement and construction of the members being such that that motion or mechanism produces not only the step-by-step movement 40 of the carriage, but also the return movement of the type levers. That mechanism is connected by means of a horizontal rod or arm with the bow that transmits the movements of the type levers to it, in that a nose provided at each of 45 these levers pushes upon said bow and moves rearwardly, whereby this mechanism is actuated and the carriage is shifted by means of the known spring provided for this purpose by a distance corresponding to one character. Besides this 50 known spring which does not constitute a member of the step-by-step motion, there is not one other spring in this mechanism which is the main cause that the touch upon the keys is so very light. The main members of said mechanism are, firstly, two parallel racks with ratchet-teeth, which are directed towards one another and from between them a narrow gap, the length of which corresponds to the length of said racks, and secondly, two rods which are arranged at right angles with respect to the racks and the 60 free ends of which form pawls that co-operate alternately with said ratchet-teeth. The two racks are rigidly connected with one another and are always subject to the pull of the above mentioned spring provided for the carriage, there 65 being transmitting members between the carriage and said racks with their ratchet teeth, and it is due to the action of said spring that at every rearward and forward movement of the said arm the racks are moved by one step, that 70 is to say, by as much as corresponds to one of the ratchet teeth. The to-and-fro motion of the said arms is effected by the swinging movement of the type levers which are operated by the key levers by the intermediary of transmission mem- 75 bers, as is all fully described hereinafter.

Besides the advantages mentioned in the first part of this introductory part of this specification, other advantages are these that the bulk and the height of the type-writing machine are 80 reduced so that it is more compact and more easily portable and therefore particularly suited for travellers.

The invention is illustrated diagrammatically and by way of example on the accompanying 85 drawing on which Figure 1 is a side-view of the mechanism for the step-by-step movement of the carriage; Figure 2 is a plan of the members shown in Fig. 1, the type lever and the key lever being, however, omitted.

90 Referring to said figures, h^0 and h^2 are straight racks, the teeth of which are directed towards one another and which co-operate with an arm a^0 and with an arm a^0 that is connected with the arm a^1 by means of a double-armed lever d^0 , by 95 which the to-and-fro motions of the arm a^1 are transmitted to the arm a^0 . That end of each of these arms which co-operate with one of the racks is designed as a pawl. The arm a^0 is subjected to the pressure of a flat spring l^1 and is held 100 by this spring in contact with an abutment pin l . When the arm a^1 is actuated by the bow b , both arm pawls co-operate with the two racks in the same manner as the roll c co-operates with the ratchet teeth e and e^1 , and it will be obvious that 105 the carriage will be moved in steps under the pull of the car spring (not shown) by the intermediary of the rope or the like h^1 . There is no spring, the force of which must be overcome by 110 the keys when any one of them is depressed, and

that being so the touch is extraordinarily light and very quick writing is rendered possible. All parts of the simple mechanism operate with perfect reliability and repairs are practically excluded.

The bow *b* is supported upon rearwardly extending lugs of the segment *n* from which the type levers *i* are suspended. The entire set of type levers can be withdrawn. That withdrawing is rendered possible by the particular configuration of the rear end of the type levers *i*, in that said end is provided with a straight oblique face *i*⁰ upon which bears the hook *j*² of the intermediate lever *j*¹. A particular advantage of this possibility to remove the entire set of type levers in a quick and easy manner resides therein that types of one character can be replaced by types of another character, and the like, such as types more fitting to another language. Such an exchange is such an easy procedure that the owner of the type-writing machine can do it himself, without skilled hands.

Concerning the manufacture of the machine great savings are obtained as regards amount of work, wages, time, and so on. The so-called type baskets can be made independent of the frame and the other parts of the machine, such as the car etc., and any of these baskets can be mounted in any of the otherwise finished frames. It is a great progress that the type levers need not be inserted singly into the machine, but that all of them can be inserted at the same time, whereby the work is greatly simplified.

Finally, I wish it also to be understood that I do not limit myself to all details shown in the drawing merely by way of example. There are, in the details, many departures possible which does not, however, constitute departures from the invention, especially from the principle embodied.

I claim:

1. In a type-writing or similar machine, in combination with the carriage, the paper roller thereon, and the type levers, a vertical segment, from the lower rim of which the type-levers are suspended; a vertical bow arranged just behind said segment; noses provided at the type levers near their suspension places and being adapted to push upon said bow when the appertaining type levers are operated by the appertaining key levers; a ratchet mechanism comprising two racks and pawls co-operating with them, said racks being subjected to the pull of the means tending to draw the carriage to the left, and an arm extending rearwardly from said feeding bow and being connected with said pawls so as to engage and disengage alternately said pawls from said racks in order to effect the step-by-step motion of the carriage, substantially as set forth. 80 85 90

2. In a type-writing or similar machine, in combination with the carriage, the paper roller thereon, and the type-levers, two racks having ratchet-teeth, the oblique flanks of which extend in different directions; pawls engaging said racks alternately and being connected with one another; a connection between said racks and said carriage, this connection being subjected to the means tending to move the carriage in steps to the left in accordance with the operation of the key levers and the appertaining type levers; a 100 feeding bow so located with respect to the type levers as to be adapted to be shifted rearwardly by any of them; an arm hinged to said bow and extending rearwardly and being connected with said pawls, all substantially and for the purpose 110 set forth. 100 105 110
